FIG. 6

FIG. 7

UNITED STATES PATENT OFFICE.

EMORY S. ENSIGN, OF BRIGHTON, MASSACHUSETTS.

EYELETING-MACHINE.

1,119,417.

Specification of Letters Patent.

Patented Dec. 1, 1914.

Application filed December 18, 1913. Serial No. 807,543.

To all whom it may concern:

Be it known that I, EMORY S. ENSIGN, of Brighton, in the county of Suffolk and State of Massachusetts, have invented certain new and useful Improvements in Eyeletting Machines, of which the following is a specification.

This invention relates to mechanism for uniting several superposed sheets of paper, or the like, so that they may be readily examined without fear of displacement of their order.

It may be considered as an improvement on eyeletting machines, in that an angular opening is punched through the paper instead of a round one, and consequently, one fastening is sufficient to prevent the sheets from swiveling on the eyelet.

Another valuable improvement consists in the fact that a simple plate of thin metal is presented to the mechanism instead of a prepared eyelet, this being pierced similarly to the sheets of paper and at the same operation. The punchings from this perforation in the metal are not severed from the plate but are carried through the perforation in the sheets of paper, in the form of projecting angular lugs of predetermined shape which are clenched on the opposite side of the paper. This perforation is preferably square in outline and is so illustrated in the drawings which accompany and form part of this specification; but it will be understood that the main function of the angular shape is to prevent the swiveling noted above.

Another feature of my invention is the means for severing these bits of metal from a continuous strip that is fed into position for perforation.

Other minor features will appear in the description which follows:

In the drawings,—Figure 1 is a side elevation of my device with certain parts broken away. Fig. 2 is a section on line 2—2 of Fig. 1, with the punch shown in elevation. Fig. 3 is a plan section on line 3—3 of Fig. 1. Fig. 4 is a partial section on line 2—2 of Fig. 1, viewed from the opposite direction to Fig. 2. Fig. 5 is a similar partial section showing the operation completed. Figs. 6 and 7 show, respectively, front and rear views of the clenched sheets.

The frame 1 is made in two parts fastened together at 2. One of these parts incloses

the punch or male die 3 and the other the female die 4. The square outline of the dies is shown by dotted lines in Fig. 3, where the female die alone is represented. The punch 3 is similar in outline and is adapted to completely sever the paper punchings as it enters the female die 4, a clearance being provided in the latter for the escape of these severed bits. Die 4 is supported on a threaded plug 5 which permits slight adjustment, but which is mainly designed to form a substantial abutment to resist the thrust of the clenching blow.

In Fig. 1, the paper P is shown in position for clenching and is yieldingly supported on a pair of flat springs 6, 6, the free ends of which are adapted to recede into openings 7 in the frame, when the clenching pressure is applied. The shape of these springs is such as to present no shoulder to oppose the proper entrance of the paper P, nor its withdrawal after clenching.

The punch 3 is firmly mounted in a reciprocating stem 8 which terminates in a head or handle 9, said stem being surrounded by a spiral spring 10 which tends to maintain stem 8, which is square in outline to prevent turning, in raised position. The guide opening for stem 8, in frame 1, is enlarged at one side to accommodate a cam-block 11, secured to stem 8 by screws 12, this cam-block having two functions to perform, as will be later described.

A cover plate 13, secured to frame 1 by screws 14, has a square opening which closely and slidably fits stem 8 on all sides and forms a stop for engaging cam-block 11 to limit the upward movement of punch 3.

The strip of metal, M, is here shown as wound upon a reel 15, from which it is fed between two guide rolls 16, 16, one of which is slidably mounted in grooves 17 in the bearings 18, secured at 19 to frame 1, tension being maintained by spiral springs 20, 20, Figs. 1 and 3. From rolls 16, the metal is introduced through an opening 21 in frame 1 and fed, by hand, against a shoulder 22, formed on each of a pair of slideable blocks 23, 23, said shoulder serving to register a prescribed amount of metal for each operation, beneath the punch or plunger 3. Blocks 23 are slidably housed within a transverse opening 24 in frame 1 and are normally held in contact with each other by spiral springs 25, 25. To insure their meeting directly below the punch 3, stop-

pins 26, 26, fixed in a plate 27 which covers the opening 24, are provided, one for each block 23, these pins 26 coöperating with their respective grooves 28 in the blocks 23 to secure the proper register. An opening 29 in plate 27, permits the passage therethrough of the severed metal plate M, as will be later described. Blocks 23 are slightly chamfered at their meeting point, as indicated at 30, Fig. 2, for a purpose which will be more fully explained later.

In operation, the sheets of paper, P, are inserted as shown in Fig. 1, an opening being provided in the frame for that purpose, 15 the metal strip M, is fed against the shoulder 22, and then a quick, sharp blow on handle 9 performs all the operations necessary to produce the result shown in Fig. 6. These operations will now be described in 20 detail. The point of punch 3, which is pyramidal in shape, perforates the metal strip, the tips of the tri-angular punchings, m, entering the groove or chamfer at 30 and serving as the entering wedge for the 25 spreading of blocks 23. As punch 3 descends blocks 23 are separated as shown in Fig. 4, where the full spreading effect of punch 3 has been exerted. Here, the shoulder 31 of stem 8 has not yet met the metal M, 30 nor has the latter been severed from the strip. To complete the spreading of blocks 23, the cam-block 11, wedge-shaped as shown at 32 in Figs. 2, 4 and 5, engages the shoulders 22 of the partly spread blocks 23 and 35 completes this part of the operation, whereupon the shoulder 31, coöperating with a block 33, which underlies the edge of opening 21 in frame 1 severs the portion of the metal strip that lies within the path of stem 40 8. This severed portion, threaded on punch 3 and held against the shoulder 31, is carried into contact with the paper, P, the projecting lugs m passing through with punch 3 and meeting the abutment of the female 45 die 4, where they are carried under the paper and clenched, as seen in Fig. 5.

Although I have illustrated the metal strip as hand-fed, it will be understood that I do not limit myself to this method, nor 50 to the other details of construction shown.

It will be noticed that the punched openings through both metal and paper are the same in area, the latter being forcibly enlarged by the projecting lugs as they pass 55 through the sheets.

What I claim is:—

1. A frame, a square punch with pyramidal point movably mounted in said frame, means for presenting a thin metallic plate, 60 within the range of operation of said punch, movable blocks mounted in said frame and adapted to support said plate when so presented, means for yieldingly retaining said blocks beneath said plate so that their meeting place shall register with the path of

motion of said point, the meeting edges of said blocks being scarfed to facilitate their separation by said punch and mechanism for causing said punch to perforate said plate and separate said blocks, said punch 70 and said blocks being adapted to coöperate in forming the material punched from said plate into four, tri-angular, projecting lugs which are integral with said plate and which surround said perforation; in combination with means for clenching said lugs. 75

2. A clenching device comprising a frame, an angular punch movable in said frame, means for presenting a thin metal plate in alinement with said punch, a pair of movable blocks mounted in said frame and adapted to support said plate when so presented, a female die mounted in said frame and adapted to coöperate with said punch, said frame being so constructed and arranged that a series of superposed sheets of paper, or the like, may be positioned within the range of operation of said punch, a shoulder formed upon said punch and means whereby said blocks may be moved from beneath said plate; in combination with mechanism for operating said punch to form said plate into an angular eyelet and clench the same through and upon said sheets by a single operation. 95

3. A clenching device comprising a frame, an angular punch with a pyramidal point movably mounted in said frame, a shoulder formed on said punch, means for presenting one end of a thin metallic strip within the range of operation of said punch, a pair of movable blocks mounted in said frame and underlying said end when so presented, said blocks being adapted to coöperate with said punch in forming an angular opening 100 through said end whereby the punchings shall assume the form of depending, angular lugs surrounding said opening and integral with said metallic strip, a female die mounted in said frame, said frame being so constructed and arranged that a plurality of superposed sheets of paper, or the like, may be placed in alinement with said punch; in combination with mechanism for causing the piercing of said end, the severing of same from the strip and the clenching of said severed and pierced end through 110 and upon said sheets. 115

4. A clenching device comprising a frame, a punch mounted in said frame, means for presenting a thin metallic plate in alinement with said punch, a laterally movable support for said plate, said frame being so constructed and arranged that a plurality of superposed sheets of paper, or the like, may be positioned for perforation by said punch, a female die mounted in said frame and in vertical alinement with said punch, a shoulder on said punch and mechanism for operating said punch to successively form 120 125 130

an eyelet from said plate, thread said eyelet on the shank of said punch, move said support laterally from beneath said plate, perforate said sheets and clench said eyelet 5 through and upon said sheets, all by a single operation.

5. A frame, a punch mounted in said frame, a shoulder formed in connection with said punch, a female die mounted in said 10 frame, said frame being so constructed and arranged that a plurality of superposed sheets of paper, or the like, may be presented for perforation by said punch, means whereby a thin metallic plate may be presented 15 in alinement with said punch; in combination with mechanism for causing said punch to form an eyelet from said plate, to perforate said sheets and completely sever therefrom the punchings from 20 such perforation, and means for clenching said eyelet through and upon said sheets.

6. A frame, an angular punch mounted in said frame, a shoulder formed in connection with said punch, a female die mounted 25 in said frame and adapted to coöperate with said punch, means for presenting a thin metallic plate in alinement with said punch, said frame being so constructed and arranged that a sheet or sheets of paper may 30 be presented for perforation by said punch and mechanism for causing said punch to successively form an eyelet from said plate, to perforate said paper and completely sever therefrom the punchings from such perforation and to clench said eyelet through and 35 upon said paper.

7. A frame, a square male die mounted in said frame, a female die mounted in said frame, a shoulder on said male die, said 40 frame being so constructed and arranged that a sheet or sheets of paper may be presented in alinement with said male die, said male die being adapted to perforate

said paper and completely sever therefrom the punchings from such perforation and 45 mechanism for causing said male die to perforate said paper and to coöperate with said shoulder and said female die in presenting to said perforation and clenching through and upon said paper a square metallic eyelet, all by a single operation.

8. A fastening device comprising means for forming a metallic eyelet whose opening is of such contour as to prevent the swiveling thereon of the material fastened, a 55 punch for perforating the material to be fastened and adapted to completely sever the punchings from such material and means for setting said eyelet, comprising a shoulder and a female die adapted to co- 60 operate with said punch; in combination with mechanism for operating the forming, perforating and setting means to form and set the eyelet by a single operation.

9. A clenching device comprising a frame, 65 an angular punch with a pyramidal point movably mounted in said frame, means for presenting a thin metallic plate within the range of operation of said punch, a laterally movable support for said plate when 70 so presented and mechanism for causing said punch to perforate said plate and move said support laterally from beneath the same, said punch and said support being adapted to coöperate in forming the material 75 punched from said plate into projecting, angular lugs which are integral with said plate and which surround said perforation; in combination with means for clenching said lugs.

In testimony whereof I have affixed my signature, in the presence of two witnesses.
